UNITED STATES PATENT OFFICE.

CHARLES E. BRADSHAW, OF WATERBURY, CONNECTICUT.

BUCKLE.

Application filed October 4, 1922. Serial No. 592,331.

To all whom it may concern:

Be it known that I, CHARLES E. BRADSHAW, a citizen of the United States, residing at Waterbury, in the county of New Haven and State of Connecticut, have invented a new and useful Improvement in Buckles; and I do hereby declare the following, when taken in connection with the accompanying drawings and the characters of reference marked thereon, to be a full, clear, and exact description of the same, and which said drawings constitute part of this application, and represent, in—

Fig. 1 face view of a buckle constructed in accordance with my invention.

Fig. 2 a sectional view on the line 2—2 of Fig. 1.

Fig. 3 an end view of the buckle detached.

Fig. 4 a face view of the same, with the lever in the open position.

Fig. 5 a plan view of the frame, with the bottom bar divided and separated to form a loop.

Fig. 6 a sectional view, illustrating a modified form of buckle-frame.

Fig. 7 a face view of the buckle illustrated in Fig. 6, with the lever in its open position.

This invention relates to improvement in buckles, and while particularly adapted for buckles for suspenders, hose supporters, and the like, are adapted for other uses. The invention particularly relates to buckles of the rustless type, which consist of a wire frame comprising an upper and lower bar and a lever pivotally connected with the upper bar. The object of this invention is to so form the frame that the web may be engaged therewith in a simple and convenient manner, without sewing, and hence decrease the amount of web used, and the invention consists in a buckle having certain details of construction as will be hereinafter described and particularly recited in the claims.

In carrying out my invention, I employ a frame which comprises a lower bar 10, sides 11 and 12, and ends 13 and 14, which form

the top bar of the frame, and on which the lever 15 is mounted, this lever comprising the usual finger-piece 16 and gripping-edge 17. These frames are usually formed from round wire, and in carrying out my improvement I shear the lower bar 12 longitudinally and separate the two parts to form an open slot, as clearly shown in Fig. 5 of the drawings. Into this slot, one end 18 of the web 19 is passed, and the two members 20 and 21 of the lower bar are brought together so as to firmly grip the end of the web. The free end of the web is passed upward between the lower bar 10 and the gripping-edge 17 of the lever by which the web is deflected over that portion of the web engaged by the lower bar.

Instead of forming the frame from a piece of round wire, it may be formed from a strip 22 of half-round wire, as indicated in Figs. 6 and 7 of the drawings, this wire being doubled upon itself, so as to practically form a single strand of round wire. The portions 23 and 24, forming the bottom bar, are separated to receive between them the end 18 of the web, which is gripped in the same way as in the construction first described.

I claim:

1. A buckle, comprising a frame formed from wire having an upper and a lower bar, a lever pivotally connected with the upper bar, and the lower bar divided longitudinally to form a loop to receive one end of a web.

2. A buckle, comprising a frame formed from wire having an upper and lower bar, and a lever pivotally connected with the upper bar, and the lower bar formed with a longitudinal slit forming a loop, through which one end of a web may be clamped.

In testimony whereof, I have signed this specification in the presence of two subscribing witnesses.

CHARLES E. BRADSHAW.

Witnesses:

DOROTHY M. MABBOTT,
JOHN T. MONZANI.
